INVENTOR.

Allie McMillan,
BY

Geo. P. Kimmel. ATTORNEY.

UNITED STATES PATENT OFFICE.

ALLIE McMILLAN, OF EMBARRASS, WISCONSIN.

ENSILAGE PROTECTOR.

Application filed March 17, 1925. Serial No. 16,259.

To all whom it may concern:

Be it known that I, ALLIE McMILLAN, a citizen of the United States, residing at Embarrass, in the county of Waupaca and State of Wisconsin, have invented certain new and useful Improvements in Ensilage Protectors, of which the following is a specification.

This invention relates to devices for protecting the contents of containers, such as silos and the like, and has for one of its objects to improve the construction and increase efficiency and utility of devices of this character.

Another object of the invention is to provide a device of this character which is expandible by gravity against the walls of the silo or other container, and which may be distended by force vertically applied to remove or change the position of the device.

Another object of the invention is to provide a device of this character comprising a central post adapted to rest upon the contents of the container, and expandible rim movably associated with said post, and a flexible element attached to said rim.

With these and other objects in view, the invention consists in certain novel features of construction as hereinafter shown and described and then specifically pointed out in the claims, and in the drawings illustrative of the preferred embodiment of the invention.

Fig. 1, is a plan view of the improved device.

Fig. 2, is a transverse section.

Fig. 3, is a side elevation on a reduced scale of the improved device arranged within a section of a conventional silo.

Fig. 4, is an enlarged detail partly in section, illustrating the construction of the expandible rim.

The improved device is designed more particularly for use in a silo to protect the ensilage, but may be employed wherever a protecting device is required, and comprises a rim portion formed of a plurality of segmental sections 10 preferably tubular, with their confronting ends normally in spaced relation, and with pins 11 disposed within the sections and bridging the gap between them. Each of the pins 11 is preferably attached as at 12 to one of the rim sections and slidable at the other end in the adjacent section and constitute guides which also serve for closing the gaps between the sections.

By this means an expandible and contractible rim is provided.

For the purpose of illustration three of the rim sections 10 are shown but this number may be changed as required.

Disposed centrally of the rim sections is a post member 13, preferably tubular, and slidable on the post is a runner member 14 having radially directed ears between which brace members 15 are pivoted at one end as shown at 16.

Formed upon each of the segmental sections 10 are spaced ears 17 between each pair of which the outer ends of the ribs 15 are respectively pivoted as shown at 18.

For the purpose of illustration two of the ribs 15 are shown associated with each of the rim sections, but this number may be changed as required.

At its lower end the post 13 is provided with a laterally directed foot 19, and attached to the foot is a pull cable 20 which extends through the post and is adapted to be operated in any suitable manner, not shown, to apply upward strain upon the post, as hereafter explained.

A sheet 21 of flexible material such as canvas or the like is attached to the rim sections, and perforated centrally to slidably engage the post 13.

Attached to the post 13 at its upper end is a head member 22 having spaced perforated ears 23 through which guide pins 24 extend, as shown, and attached to the ears 17 are flexible stay members such as chains 25, and attached to each of the stay members is a flexible pull member, such as a chain 26, each pull member passing beneath one of the guide pins 23 and thence upwardly to a ring 27 common to all of the pull members, a pull cable 28 leading upwardly from the ring as shown.

For the purpose of illustration the improved device is shown in Fig. 3 arranged within a silo structure, a section of which is shown at 29 in Fig. 3, and a portion of the ensilage indicated at 30 with the foot member 19 resting on the latter.

When the improved device is to be applied it is lifted by power applied to the pull cable 28, to cause the pull members 26 to contract the rim sections and reduce the diameter of the device to a sufficient extent to permit it to be disposed within the container, for instance a silo structure, and lowered

therein until the foot 19 rests upon the ensilage, as shown in Fig. 3. The strain upon the pull member 28 is then released, to permit the rim member and its attachments to settle downwardly by gravity and expand the rim sections against the inner walls of the container, and thus form a relatively airtight closure within the container and protecting the ensilage or other contents of the 10 container.

When thus employed, the pull member 20 is ineffective, but if the device is to be located within the container at any point spaced above the ensilage or other contents, 15 a pulling force is applied to the pull member 20 to hold the foot member 19 at the point where the protector device is to be located and held in that position, and when the other pull member 28 is released, the expansion of the rim members will hold the device at the new location, and this location will be maintained so long as strain is applied to the supplemental pull member 20.

A stop collar 31 is disposed on the post 13 and held at any desired position by a set screw 32, to limit the upward movement of the runner 14.

The improved device is simple in construction, can be constructed of any required size, 30 or of any required material or combination of materials.

The post 13 may be of any required length, so that the space between the ensilage and the protector device may be of 35 any required area.

When a portion of the ensilage is to be removed, the protector device may be elevated to provide space for the workman, and then lowered again to protective position when 40 the required quantity of the ensilage has been removed.

The preferred embodiment of the invention is disclosed in the drawings and set forth in the specification but it will be understood that modifications within the scope 45 of the claimed invention may be made in the construction without departing from the principle of the invention or sacrificing any of its advantages.

Having thus described the invention, what 50 is claimed as new is:

1. In a device of the class described, a rim 55 of tubular segmented sections with their terminals movable toward and away from each other, guides slidably fitted in the ends ad-

jacent to each other of the sections for closing the gaps therebetween, a flexible sheet connected to said segmental sections, a central post member, a runner member slidable on said post, a plurality of ribs pivoted at 60 the ends respectively to said rim sections and to the runner, and means for adjusting said sections vertically to expand and contract the same.

2. In a device of the class described, a rim 65 of tubular segmental sections with their terminals movable toward and away from each other, guides slidably fitted in the ends adjacent to each other of the sections for closing the gaps therebetween, a flexible sheet 70 connected to said segmental sections, a tubular post having a laterally directed foot portion, a runner member slidable on said post, a plurality of ribs pivoted at the ends respectively to said runner and to said rim sections, a pull member attached to said foot portion and extending through said tubular post, and means for adjusting said rim sections 75 vertically to expand and contract the same.

3. In a device of the class described, a rim 80 of tubular segmented sections with their terminals movable toward and away from each other, guides slidably fitted in the ends adjacent to each other of the sections for 85 closing the gaps therebetween, a flexible sheet connected to said segmental sections, a central post member, a runner member slidable on said post, a guide member attached to said post, a plurality of ribs pivoted at 90 the ends respectively to said rim sections and to the runner, a plurality of pull members 95 attached relatively to said rim members and leading through said guide member and adapted to be operated to apply strain to the rim members to contract the same.

4. The combination with an enclosure of a rim of tubular segmental sections with their terminals movable toward and away from each other, guides slidably fitted in the 100 ends adjacent to each other of the sections for closing the gaps therebetween, a flexible sheet connected to said segmental sections, and means for expanding said segmental sections, to cause the rim sections to be 105 pressed against the interior of the enclosure.

In testimony whereof, I affix my signature hereto.

ALLIE McMILLAN.
